UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 23,606, dated August 28, 1894.

Application filed August 3, 1894. Serial No. 519,879. Term of patent 3½ years.

To all whom it may concern:

Be it known that I, CHARLES BOOZE, a citizen of the United States, residing at Buffalo, in the county of Erie and State of New York, have invented and produced a new and original Design for Wall-Paper, of which the following is a specification.

The design consists of an arrangement of ornamental scrolls on which are placed the figure of a lion rampant, with fleur-de-lis ornaments placed at certain distances apart around said scrolls and figure, and small fleur-de-lis ornaments forming a back ground, as represented in the accompanying drawing.

15 The border or upper portion of the design is formed of shield-like ornaments formed of ornamental scrolls with the figure of a lion ram-paint on each side of said ornaments as shown in the drawing. A fleur-de-lis ornament is arranged at the top of the shield ornaments 20 and small fleur-de-lis ornaments form the back ground for the border as shown in the drawing.

What I claim is—

1. The design for wall paper herein shown 25 and described.
2. In the design for wall paper the border herein shown and described.

Witness my hand this 31st day of July, 1894.

CHARLES BOOZE.
